United States Patent Office.

GEORGE CROMPTON, OF WORCESTER, MASSACHUSETTS.

Letters Patent No. 95,092, dated September 21, 1869.

IMPROVEMENT IN LOOM.

The Schedule referred to in these Letters Patent and making part of the same.

To all whom it may concern:

Be it known that I, GEORGE CROMPTON, of Worcester, in the county of Worcester, and State of Massachusetts, have invented Improvements in Looms; and I do hereby declare that the following, taken in connection with the drawings which accompany and form part of this specification, is a description of my invention, sufficient to enable those skilled in the art to practise it.

My present invention relates particularly to the organization of the drop-box mechanism and shipper-mechanism of that class of fancy-looms in which the boxes are distributed, as indicated, by a single pattern-chain or cylinder, by means of sets of tappets on a tappet-shaft, one tappet raising or lowering the boxes one space, and another tappet moving the boxes a double space, so that any one of the three boxes may be gained at will.

My improvement consists in combining with the tappet-shaft, and the two tappets at each end thereof, two auxiliary ratchets and pawls and an auxiliary tappet-working shaft, geared to the tappet-shaft, by means of which movement may be imparted to each or either of the tappets at the opposite end of the shaft, such movement being independent of the movements imparted to the tappets adjacent to the ratchets; and

The invention further consists in the peculiar organization of the belt-shipper mechanism.

The drawings represent a loom or loom-frame with my improvements embodied thereupon.

A shows the loom in end elevation.

B is a side elevation, showing the box-actuating mechanism at the opposite ends of the loom, the central parts of the frame, shafts, beams, and lay being broken away.

C is a horizontal section on the line xx , (the central parts being broken away, as at B,) showing the box-actuating-mechanism in plan.

a denotes the frame.

b, the lay.

c, the crank-shaft that operates the lay.

d, the cam-shaft that operates the pawls which actuate the ratchets of the tappet-shaft *e*, whose tappets effect the changes of the boxes.

This tappet-shaft carries, at one end, two tappet-wheels, *f g*, and, at the opposite end, two other tappet-wheels, *h i*, each set of tappets effecting the movements of the set of boxes, *k*, on the corresponding end of the frame.

Each set of boxes is supported upon a vertical rod, *l*, at the end of a lever, *m*, fulcrumed at *n*, a pin projecting from the opposite end of the lever being pressed up toward or against the peripheries of the two tappets at the corresponding end of the tappet-shaft.

The tappet-shaft *a* carries four ratchets, *o p q r*; one

for each tappet; and with each ratchet engages, at proper times, a pawl, *s*, pivoted in a swinging carrier, *t*, which is thrown forward by the cams on the cam-shaft, and back by a suitable spring.

Each pawl is hung to a finger, *u*, resting upon a pattern-chain or cylinder, *v*, each pawl-finger holding its pawl above its ratchet, or letting it down into position to turn its ratchet at the forward movement of the pawl-carrier, as may be determined by the pattern-mechanism.

All the ratchets but one are loose upon the tappet-shaft.

The outer loose ratchet, *o*, is fixed to the outer tappet-wheel, *f*, and the next tappet-wheel, *g*, is fixed to the adjacent ratchet *p*, (which also turns upon the shaft,) and, as the lever-pin under these two tappets passes from the larger to the smaller radius (or *vice versa*) of the smaller tappet, it effects a movement of the boxes one space, while, when it passes from the larger to the smaller radius (or *vice versa*) of the larger tappet, it effects the movement of the boxes two spaces, so that by means of the two tappets, either box of the set of boxes at this end of the loom can be brought opposite the race.

The third ratchet, *q*, is fast upon the shaft, as is also one of the tappet-wheels at the opposite end of the shaft, so that movement of this ratchet by its pawl effects the movement of the said fast tappet-wheel and corresponding movement of the shuttle-boxes at such opposite end of the lay.

As, in order to make the other or fourth tappet-wheel independent in its movements from the last-named tappet-wheel, it and its ratchet *r* must both be loose upon the shaft, an intermediate mechanism is necessary for transmitting movement to it from its ratchet *r*, which mechanism is as follows:

Fixed to the ratchet *r* is a gear-wheel, *w*, which meshes into and drives a gear, *x*, fixed on one end of an auxiliary shaft, *y*, at whose opposite end is a similar gear, *z*, meshing into and driving a gear, *j*, fixed to the fourth tappet-wheel, movement imparted to the fourth tappet-wheel with the employment of only one tappet-shaft, one pattern-mechanism, and one set of pawls, any one or more of the tappets being moved independently of or in conjunction with any other one or more of the tappets, as will be readily understood, the two tappets at one end of the tappet-shaft corresponding to those at the opposite end thereof, as relates to the movements of the boxes affected by them.

a² denotes the shipper-fork, mounted on a rocker-arm, *b²*, and fixed to one end of a connecting-rod, *c²*, whose other end is jointed to one arm of a bent lever, *d²*, pivoted upon a bracket extending from the frame *a*, the other arm of this lever having a slot, *e²*, in which

works a pin projecting from a vertical shipper-lever, f^2 , at one end of the frame a , the upper part of this shipper-lever travelling in a guide-slot, g^2 , at one end of which it is retained by a notch, h^2 , except when released from such notch, when it is carried to the opposite end of the notch by a suitable spring.

Turning in bearings at the end of the frame a , at the bottom of the breast-beam, is a rocker-shaft, i^2 , on the end of which, next to the shipper-lever, are two arms, k^2 l^2 , while, at the opposite end of the beam, said shaft carries a handle, m^2 .

The upper arm k^2 projects toward the shipper-lever, and, by pushing the handle m^2 toward the frame, said arm pushes the lever out from its stop-notch, the lever then springing down to the end of its slot, thereby turning the bent lever d^2 , and knocking off the shipper-fork.

The arm l^2 projects down from the shaft in front of a finger, n^2 , projecting down from the outer end of a lever, o^2 , whose other end is pivoted on the under side of the breast-beam.

Just inside of the end-piece of the frame a , a projection, p^2 , extends down from this lever, as seen at D and E. When the "dagger" on the lay strikes this projection, it pushes back the finger n^2 , causing the finger to press against the arm l^2 , projecting down from the shaft i^2 , thereby turning the rocker-shaft, and causing the upper arm k^2 to push the shipper-lever from its notch, and knocking off the loom.

The shipper-lever is drawn back into its notch, from the opposite end of the loom, by means of a hook, q^2 , at the end of a rod, r^2 , running under the breast-beam, and jointed, at its opposite end, to a hand-lever, s^2 , by working which the hook is drawn back, bringing with it the shipper-lever, the latter springing into its notch when it comes opposite thereto.

I claim, in combination with a box-indicating pattern-mechanism at one end of the loom, and with two tappet-wheels and their ratchets at the same end of the loom, and loose upon the tappet-shaft, the two other ratchet-wheels on the same end of the shaft, and the two tappet-wheels at the opposite end of the shaft, one of said last ratchet-wheels and its tappet being fast to the shaft, and the other of said ratchet-wheels being loose upon the shaft, and imparting movement to its tappet-wheel through the auxiliary shaft geared to said last-named ratchet-wheel and tappet-wheel, substantially as shown and described.

Also, in combination with the shipper-lever f^2 and rocker-shaft i^2 , the arm l^2 , depending from such lever, and operated by the finger n^2 , on the end of the lever o^2 , substantially as described.

GEO. CROMPTON.
